UNITED STATES PATENT OFFICE.

FERDINAND MORA CANDA, OF NEW YORK, N. Y.

BALL-ROLLING APPARATUS.

1,419,817.

Application filed August 27, 1919. Serial No. 320,174.

Specification of Letters Patent. Patented June 13, 1922.

To all whom it may concern:

Be it known that I, FERDINAND MORA CANDA, a citizen of the United States of America, and a resident of New York, in the county of New York and State of New York, have invented certain new and useful Improvements in Ball-Rolling Apparatus, of which the following is a specification.

My invention relates to apparatus for forming balls, and is particularly intended for forming, from wrought iron or steel, balls adapted to be used in crusher mills and the like, but is also adapted and intended for forming balls of various other materials and for other uses,—for example, lead shrapnel bullets, lead shot, glass balls of various types and uses, and even balls of non-metallic materials, such as pills used in medical practice, confectionery articles, etc. More particularly, however, I contemplate use of apparatus embodying my invention for forming from steel, particularly hard steel, balls of relatively large diameter, particularly intended for use as crusher balls, since at the present time large diameter crusher balls are made by a process, relatively expensive as compared with rolling operations, and involving the use of presses or hammers. In mentioning the above, however, I do not intend to suggest that I do not also contemplate the use of apparatus embodying my invention for making balls of smaller size, for my apparatus is adapted for making small balls as well as large balls. In the machine herein described two annularly related rolling members are used, one of these members, usually the inner one, being helically grooved, (though, as explained hereafter, the outer member may be helically grooved and the inner member ungrooved, or one may have a helical groove and the other a straight groove), and the material to be formed into balls is introduced into the space between these members, one of which rotates with respect to the other, and by the action of said grooves (or, to be more precise, by the action of the ribs between which the grooves are) the said material is not only drawn along between said members in a generally axial direction, but is also formed into balls, which finally issue from between said members. Owing to the fact that the helical groove or grooves of the apparatus may have any desired number of turns, and any desired pitch, the rate

of "reduction" of the material acted on, i. e., its change of shape, may be slow or quick, as desired, and may be more rapid in one portion of the apparatus than in another, if desired; and this without variation in the diameter of the apparatus; also, and for similar reasons, the character of the treatment to which the material acted on is subjected may be varied greatly, as may be desirable in the treatment of various materials.

I may say at this point that while my apparatus is particularly intended for the production of articles of generally spherical form, yet it is obviously adapted for the production of articles of other forms but generally of the nature of objects of rotation; for example, ellipsoids; and such objects I include within the general term "balls."

I will now proceed to describe my invention with reference to the accompanying drawings, in which various forms of apparatus embodying my invention are illustrated, and will then point out the novel features in claims. In the said drawings:—

Figure 1 is a side elevation, and Figure 2 an end elevation of my apparatus, in elemental form; Figures 3, 4, 5 and 6 are elevations of the two rolling members in various alternative structural forms, the outer rolling member being shown in central longitudinal section; Figure 7 shows an end view of the Figure 6 arrangement; Figure 7^a is an end elevation of a modified form of the arrangement of Figures 6 and 7; Figure 8 is a view similar to Figure 6, illustrating an alternative construction; Figures 9, 10, and 11 are other views similar to Figures 3, 4 and 5, but illustrating further alternative constructions; Figure 12 is a fragmentary end elevation of the construction shown in Figure 11; Figure 13 is a view similar to Figures 3, 4 and 5, except that a plain stationary mandrel and a grooved rotatable shell are shown; Figure 14 is a view similar to Figures 3, 4 and 5, except that the parts are shown with their axes vertical instead of horizontal; Figure 15 is an elevation of complete ball rolling apparatus including driving means, yielding pressure means employed in connection with a shell composed of separable segments, and means for holding the material to be worked into balls, while it is being fed into the ball forming apparatus—a certain delivery chute being

105

110

shown in section; Figure 16 is an end elevation and partial section of the ball rolling apparatus of Figure 15, illustrating the segmental construction of the shell and the connection of the yielding pressure means therewith; Figure 17 is a fragmentary side elevation of ball forming apparatus provided with an alternative form of work holding means; and Figure 18 is a transverse section 10 on the line 18-18 of Figure 17.

Referring first to Figures 1 and 2: 1 designates a suitable housing, adapted to contain a suitable shell 2, the latter constituting one of the ball rolling members, as 15 hereinafter described, and 3 designates the other ball rolling member, being a mandrel mounted for rotation in a bearing pedestal 4, and arranged to be driven by any suitable means, as for example a gear wheel 5. As 20 will be pointed out more fully hereafter, it is immaterial whether shell 2 or mandrel 3 rotate, and in fact, both may rotate; what is important is, that the one rotate with respect to the other; and so long as this is the 25 case, they may even rotate in the same direction, though at different rotative speeds. At least one of the two ball-rolling members, 2 and 3, is commonly helically grooved, and in the drawings I illustrate various 30 forms of shells and mandrels.

In Figure 3 I show one such combination of shell and mandrel. It is to be understood, with reference to this and similar succeeding views, that the shell and mandrel 35 shown are adapted for use in the structure shown in Figures 1 and 2. In Figure 3, 2^a designates a shell of cylindrical contour internally, and 3^a a taper mandrel, helically grooved, the helical groove starting with a 40 nearly flat contour near the smaller end of the mandrel, and gradually merging into an approximately semi-circular contour at its larger end. In rolling balls with this apparatus, the material to be rolled, preferably 45 in the form of a round bar, is introduced between the shell and mandrel at that end at which the clearance between said members is greatest, i. e., at the right-hand end, in Figure 3, and such material, as so introduced, is engaged by the helical rib or thread 50 6 of the rotating mandrel, and thereby the said material acted upon is gradually drawn into the space between the mandrel and shell, and is gradually grooved, while being 55 rotated between the mandrel and shell, so that said material is eventually divided, progressively, into a series of balls, which issue at the enlarged groove, 7, at the left-hand end of the apparatus. In general, the balls 60 so formed will be of nearly perfect spherical contour; but for many purposes, as for example, balls intended for use in crusher mills, it is immaterial whether the balls be of nearly perfect form, and in particular it 65 is immaterial whether the balls have some-

what rough or imperfect surfaces near the axes about which they have been turned in the process of rolling; and indeed, it is immaterial if the balls be not completely severed from one another as they issue into the 70 groove 7; for if they be connected by small necks as they issue, they are easily broken apart from one another.

In general, the clearance space between the shell and mandrel should gradually contract, and such contraction may be obtained by employing a tapered mandrel and a cylindrical shell, as indicated in Figure 3, or by employing a mandrel and shell both of which are tapered, as indicated in Figure 4, 75 80 wherein 2^b and 3^b designate the shell and mandrel respectively. Some materials acted upon are not only deformable but also more or less compressible, while other materials are deformable but practically incompressible; for which reason it may be necessary 85 to use a mandrel and a shell such as shown in Figure 5, wherein both shell and mandrel, here designated by numerals 2^c and 3^c respectively, are tapered in the same sense. 90 The important thing is, that sufficient material be taken in by the first turn of the thread of the mandrel to insure substantial filling of the final groove of the mandrel without overplus of material, bearing in 95 mind the degree of compressibility of the material; and the intelligent designer, having knowledge of the qualities of the material to be rolled, will readily design the shell and mandrel to accomplish this end. 100

In Figures 3, 4 and 5 the working surface of the shell is not grooved, and in such apparatus the material acted upon will in general have a planetary rotation about the axis of the mandrel and shell (which two 105 members have, in general, the same axis) in addition to rotation about its own axis. But if preferred the shell may itself have a groove 8, (Figure 7) parallel to the axes of the mandrel and shell, whereby the planetary rotation of the material acted upon is 110 prevented; and in such case, it may be convenient to provide in this groove 8 anti-friction rollers 9, to facilitate rolling of the material acted on. In such a case, the two 115 rollers 9 become in fact one single rolling member, complementary to the grooved mandrel, and the shell (2^a) becomes a mere frame for the support of the rollers; consequently, and as indicated in Figure 7^a, a 120 frame 2^c may be substituted for the shell. The rollers, even though supported by a mere frame, are to be regarded as constituting a segment of an annulus, with respect to the mandrel. 125

As indicated in Figure 7, a plurality of grooves 8, and corresponding plurality of rollers 9, may be provided about a single mandrel, so that a plurality of rods to be converted into balls, may be in process of 130

treatment at the same time. As indicated in Figure 8, the rollers 9 may be inclined with respect to the axis of the mandrel, so corresponding, in that respect, to a shell 2 having an internal taper; and since I have shown that the shell may be tapered in either direction, according to requirements of circumstances, so, obviously, the rollers 9 may be inclined in either direction, according to 10 circumstances.

The apparatus shown in Figures 3 to 8 inclusive work into ball form material having an initial diameter slightly less than that of the finished balls. In Figures 9 to 15 12 inclusive I show apparatus adapted to produce balls from rods having, initially, a diameter slightly greater than that of the finished balls. This, of course, involves the initial grooving of the rods to a width between 20 grooves somewhat less than the diameter of the finished balls. Figure 9 illustrates one such apparatus, the mandrel, 3^t, having ribs 6^t which are of the same pitch throughout, but are broad in the initial portion of the mandrel but grow progressively narrower, the groove between them growing progressively wider, in accordance with the progressively increasing breadth of the partly formed balls. The contour of the 25 groove is such as to tend to force the material at the sides of the partly formed balls up toward the sides and center thereof. In Figure 10 another such apparatus is shown, the ribs, 6^g, being of the same breadth throughout, but of progressively increasing pitch, so that the groove between the ribs grows progressively wider, as in Figure 9. The arrangement shown in Figures 11 and 30 12 is similar to that of Figure 10, except that the initial turn, 6^h, is separated from the other turns of the rib 6^h, and is radially perpendicular to the axis of the mandrel and formed as a cutter, which will completely sever the rod, as introduced, into 35 separate cylinders, which thereafter will progress separately through the machine, being formed into balls, however, in the same manner as if they were connected.

As indicated in Figure 13, the mandrel, 50 3^t, here designated as 3^t, may be stationary and plain-surfaced, and the shell, here designated as 2^t, may rotate and may be grooved helically; 4^t designating bearings for the rotating housing 1^t of this form of the apparatus, and 5^t designating gear teeth provided on the housing whereby the shell may be rotated. This form of apparatus is of course the mere converse of that shown in Figure 3. As indicated in Figure 14, the 55 axes of the mandrel and shell may be vertical instead of horizontal. This form of apparatus is particularly well adapted to work on material in the form of blocks already cut to lengths proper for forming balls 60 individually. Obviously the various alterna-

tive features of structure hereinbefore illustrated may be employed in vertical apparatus as in horizontal apparatus.

It will furthermore be understood that in any of the constructions illustrated, the 70 surface of the mandrel, or the surface of the shell (including the surfaces of the rolls 9 in Figures 7 and 7^a), or both, may be roughened, as by "knurling" or the like, to improve the driving qualities of the apparatus 75 with respect to the material being worked. This is a common rolling expedient. In Fig. 6, I have indicated that the mandrel and rolls are roughened in this manner.

Since in most of the forms of apparatus 80 shown the rods from which the balls are formed have a planetary motion during their progress through the apparatus, it is desirable, particularly when the bars are of large diameter, to provide means for supporting 85 the bars in such manner that they will follow this planetary motion, in whole or in part, prior to their entry into the ball-making apparatus proper. Figure 15 illustrates one such apparatus. Two vertical 90 rods, 10, provided with roller carrying hooks 11 at their lower ends, are mounted on crank-pins of cranks 12 and 13, cranks 13 being on a shaft 14 driven by suitable gearing 15, a vertical shaft 16, and other gearing 17, from the main driving gear 5. Rods 10 are cross-connected, for stiffness, by a suitable frame 18. 19 designates the rod being fed into the machine. It will be apparent that the hooks 11 have a circular motion 95 corresponding to the planetary motion of the rod 19. The gearing 15 and 17 will be proportioned, in design, to impart motion to hooks 11 at the proper rate.

Figures 17 and 18 illustrate an alternative 100 means for the same purpose. A disk 20 is mounted loosely on an extension of the mandrel 3, and is provided with gear teeth whereby it may be rotated by driving means 21 at a suitable rate. In this disk 20 is an 110 aperture 22 through which the rod 19 to be fed into the ball forming machine may pass. A strut 23 is provided with a similar aperture, which, however, is coaxial, or substantially so, with the mandrel 3. The rod 19, being hot and therefore flexible, will readily pass from the axial aperture in strut 23 to the eccentric aperture 22.

Figure 16 also illustrates that the shell 1^a of the ball-forming apparatus may be 115 formed in separate and separable segments 2^k, movable radially outward, but normally pressed inward by yielding pressure means, such as are employed for pressing together 120 the rolls of ordinary rolling mills; for example, rams 24 of hydraulic cylinders 25. This construction, which is of course applicable to the shells of any of the various types of ball-making apparatus previously 125 illustrated and described, permits yielding 130

in case the material being worked is so hard as to put exceptional stress on the apparatus; it also permits regulation of the pressure exerted on the material, just as does

5 the adjustment device of an ordinary rolling mill.

26 in Figure 15 designates a delivery chute designed to receive the finished balls and deliver them at a desired point. Of course 10 it may be applied to any of the previously illustrated forms of apparatus.

What I claim is:—

1. In a ball rolling apparatus, the combination of two rolling members annularly 15 related relatively, both members being fixed against axial movement, one of said members mounted for rotation with respect to the other, and one of said members provided with means for drawing the material 20 acted on in a generally axial direction between said members, one of said members being provided with means for reducing the material acted upon to ball form.

25 2. In a ball rolling apparatus, the combination of two rolling members annularly related relatively, both members being fixed against axial movement, one of said members mounted for rotation with respect to 30 the other, and one of said members provided with helical grooves adapted to draw the material acted on in a generally axial direction between said members and to reduce such material to ball form.

35 3. In a ball rolling apparatus, the combination of a mandrel and a shell completely enveloping said mandrel circumferentially, both mandrel and shell being fixed against axial movement, one of said members 40 mounted for rotation with respect to the other, one of said members being provided with means for drawing the material acted on in a generally axial direction between said members, and one of said members being provided with means for reducing the material acted upon to ball form.

45 4. In a ball rolling apparatus, the combination of a mandrel and a shell completely enveloping said mandrel circumferentially, both mandrel and shell being fixed against axial movement, one of said members 50 mounted for rotation with respect to the other, and one of said members provided with helical grooves adapted to draw the material acted upon in a generally axial direction between said members and to reduce such material to ball form.

55 5. In a ball rolling apparatus, the combination of two rolling members annularly 60 related relatively, both members being fixed against axial movement, one of said members mounted for rotation with respect to the other, and one of said members provided with a helical groove, the said members adapted by reason of their relative ro-

tatability to draw between them, in a generally axial direction, material to be acted upon, and to form such material into general ball-shape.

6. In a ball rolling apparatus, the combination of two rolling members annularly related relatively, both members being fixed against axial movement, one of said members mounted for rotation with respect to the other, and one of said members provided with a helical groove the profile of which varies progressively from an initial form adapted for the reception of the material to be acted upon to a form corresponding to that of the finished article. 70

7. In a ball rolling apparatus, the combination of two rolling members annularly related relatively, one of said members mounted for rotation with respect to the other, one of said members provided, on 75 its face adjacent to the other said member, with a helical groove, and one of said members tapered on its face adjacent to the other said member.

8. In a ball rolling apparatus, the combination of two rolling members annularly related relatively, both members being fixed against axial movement, one of said members mounted for rotation with respect to the other, said members being provided, on 85 their adjacent faces, with ball-forming grooves, one of which is helical.

9. In a ball rolling apparatus, the combination of two rolling members, one of which is rotatably mounted with respect to 100 the other, one of said members comprising a helical ball-forming groove and the other of said members comprising a plurality of rotatable rollers together forming a coacting groove.

10. In a ball rolling apparatus, the combination of a rolling member having a helical ball-forming groove, and complementary helical rib, the width of said groove varying progressively, the initial portion of 110 said rib being sharp and constituting a cutter to sever the material acted on into separate blocks, and means for holding material to be acted on in said groove.

11. In a ball rolling apparatus, the combination with ball-rolling means adapted to impart a planetary motion to the material acted on while drawing it in and forming it into balls, of supporting and guiding means for the material acted on arranged 120 to follow such planetary motion.

12. In a ball rolling apparatus, the combination with ball-rolling means adapted to impart a planetary motion to the material acted on while drawing it in and forming it 125 into balls, of supporting and guiding means for the material acted on arranged to follow such planetary motion, and means for driving such supporting and guiding means.

13. In a ball rolling apparatus, the com- 130

bination of a plurality of coacting ball-
rolling members, one of which is formed in
a plurality of similar segments, and yielding
pressure means tending to force said said
5 segments toward another of said members.

14. In a ball rolling apparatus, the com-
bination of a mandrel and a shell annularly
related, said shell being formed in a plu-
rality of similar segments, and yielding

pressure means tending to force said seg- 10
ments together radially.

In testimony whereof I have signed this
specification in the presence of two sub-
scribing witnesses.

FERDINAND MORA CANDA.
